Douglas S. Stewart

ATTORNEY

UNITED STATES PATENT OFFICE.

DOUGLAS STUART SPENS STEUART, OF LONDON, ENGLAND.

HEADGEAR ATTACHMENT.

Application filed October 24, 1927, Serial No. 228,363, and in Great Britain October 25, 1926.

The present invention relates to improvements in or relating to headgear attachments for listening devices such as receivers and the like, and also for use in conjunction therewith, with devices for holding transmitting devices in position.

The invention, while being more particularly applicable for headgear attachments for telephone receivers, is also applicable for 10 headgear attachments for listening tubes and speaking tubes. In order to apply a headgear attachment to the head it is usually necessary to employ two hands for holding the receivers apart while placing in position on 15 the head and for removing therefrom.

One of the objects of the present invention is to enable a headgear attachment to be affixed to the head by a single hand, and according to one feature of the present invention this is attained by providing means adjacent one side of the head in the vicinity of the listening device for effecting the opening of the attachment so as to permit it to be placed on or removed from the head, so that 20 the hand, after placing the listening device to the ear in a similar manner to which an ordinary telephone receiver is placed and adjusting it to the most comfortable position, can release the attachment so that it will close 25 round on the other side of the head and effectively hold the receiver in position after the hand has been removed. Other arrangements for effecting the opening of a headgear attachment so as to permit it to be placed on or 30 removed from the ear have been provided with controlling means above the head so that the adjustment of the receiving devices to the ear is very indirect and not nearly so conveniently attained as by the present invention.

Another feature of the invention concerns the provision of a spring controlled drum located at one side of the headgear attachment having a band connected thereto of flexible 45 material, such as ribbon, leather or the like, and tensioned thereby, which band extends to the other side of the attachment and so presses on the head and avoids the discomfort of the usual constructions. This is particularly of 50 value in constructions such as the present where pivoted arms are employed instead of a continuous strip of metal.

A further feature of the invention is an

arrangement by which a mouthpiece may be held in position in front of the mouth by a 55 connection extending from the headgear attachment.

These and other features of the invention will be better understood by referring to the accompanying drawings, in which the single 60 figure is a view in front elevation, showing the headgear attachment as fitted to the person. As here illustrated, the headgear attachment comprises two arms 11 and 12 pivoted at 13. The arm 11 has an extension 65 piece 14 and has a slot 15 at its outer end. A pin 16 on the end of a rod 17 engages in the slot 15, so that by moving the rod 17 up and down, the arm 11 can be moved from the position shown to the dotted position. 70 The arms 11 and 12 are preferably tubular and the arm 12 is provided with a slot whereby the rod 17 can slide up and down therein. To the rod 17 a handle member 18 is attached, as shown, while to the arm 12 a handle member 19 is attached. These two handle members are provided with pins 20 and 21, over which fits a helical spring 22, which acts normally to hold them apart, as shown, and so forces the rod 17 upwards, and therefore 80 causes the arm 11 to press against the other side of the head. The arm 11 carries at its extreme end a pivoted member 23, and a cylindrical drum 24. This cylindrical drum is provided internally with a clockwork 85 spring 25 tending to rotate the drum counter-clockwise. To the surface of the drum is attached a band 26, preferably of light flexible material, such as ribbon, leather or the like. The other end of the band 26 is connected to the end of the arm 12 so that the band is normally tensioned, as shown. At 90 the end of the pivoted member 23 an ear pad 27 is pivoted, which pad is adapted to adjust itself to the ear or against the side of the head of the user when in position with the minimum amount of discomfort. At the end of the arm 12 is a support 28 for an electromagnetic receiver 29 fitted with an ear pad 30. The receiver is pivoted in the support 28 so 100 as to adjust itself to the ear. Connected to the receiver or to the end of the arm 12, whichever may be more convenient, is a flexible connecting link 31. This connecting link is made of suitable material so as to support in 105 any position to which it may be put a mouth-

piece 32 connected to the end of a flexible tube 33 leading from a fixed transmitter attached to an instrument from which the cord 34 extends to the receiver. The purpose of this connecting link is that when the receiver is applied to the head the mouthpiece comes directly in front of the mouth and the user can talk with his hands perfectly free. To apply the receiver to the head the receiver would usually be brought to the position shown in dotted lines, with the manually operating members 18 and 19 pressed together so that the relative position of the arm 11 to the arm 12 would be as shown in dotted lines. While the hand is still pressing the two members 18 and 19 together, the electromagnetic receiver would be adjusted to the most comfortable position for hearing. Actually in connection with telephone conversations it will be possible to ascertain whether the call is for the party concerned or for another party. If it was not for him, the called party could at once replace the receiver without affixing the headgear attachment. If it was for the party who had lifted the receiver, he would then, having affixed the receiver to his ear, release his grip so that the spring 22 would come into play to force the members 18 and 19 apart, and thereby cause the arm 11 to move to the position shown in full lines. The band 26 would then engage the head in a manner likely to cause the least possible disturbance, while the ear pad 27 would adjust itself to a comfortable position on the other side of the head. The hand could then be finally removed, any further slight adjustment could be made if required, and the subscriber would have both hands free. In connection with pillar-type instruments, for which the invention is particularly suitable, the flexible tube 33, which may be of the character described in my copending application Serial No. 242,941, filed Dec. 27, 1927, and which extends from the transmitter of the pillar set to the mouthpiece 32, may be brought by means of the connecting link 31 in front of the mouth of the user at the same time as the receiver is placed in position near the ear. With such an arrangement both hands would be free immediately the receiver was adjusted and the desk in front of the subscriber would be clear so that he could either read from papers on the desk or write as may be desired.

55 I claim:

1. In combination, a listening device, a headgear attachment to which said listening device is secured, means associated with said headgear attachment whereby said attachment can be opened to permit the listening device to be placed to the ear, and means located directly adjacent said listening device whereby the attachment can be closed to grip the head.

2. In combination, a listening device, a headgear attachment to which said listening device is secured, means adapted normally to act to bring the ends of said attachment towards each other, and means located exclusively at one side of said headgear attachment to force the ends of said attachment apart and permit the listening device to be placed on or removed from the head.

3. In combination, a headgear attachment comprising two arms adapted to engage opposite sides of the head and pivoted with respect to each other, a listening device secured adjacent to the end of one of said arms, a spring adapted to cause said arms to move towards each other, and manually controlled means located exclusively at one side of the headgear attachment adjacent to the listening device whereby said arms can be forced apart for placing said attachment on or removing it from the head.

4. In combination, a listening device, a headgear attachment adapted to secure said listening device in position on the head, a spring controlled drum located at one side of said attachment, and a band of flexible material having one end secured to said drum and tensioned thereby, and the other end secured to the other side of said attachment.

5. In combination, a listening device, a headgear attachment therefor comprising a pair of arms pivoted with respect to each other, a spring controlled drum located at the end of one of said arms distant from the pivot, and a band of flexible material having one end secured to said drum and tensioned thereby and the other end secured to the end of the other arm distant from the pivot.

6. In combination, a listening device, a headgear attachment therefor comprising a pair of arms pivoted with respect to each other, a spring controlled drum located at the end of one of said arms distant from the pivot, a band of flexible material having one end secured to said drum and tensioned thereby and the other end secured to the end of the other arm distant from the pivot, and means for forcing the ends of said arms apart and extending said band to permit it to be positioned over the head.

7. In combination, a headgear attachment comprising two arms adapted to engage opposite sides of the head and pivoted with respect to each other, a listening device secured at the end of one of said arms, a manually controlled member secured to said arm, an extension piece on the said arm, a second manually controlled member located within hand-grip distance of the first-named member, a link connecting the second-named member, with said extension piece, a spring which normally tends to force the two manually controlled members apart to cause the ends of said arms to approach towards each

other, and means whereby if said members are pressed together by the hand said arms are forced apart to permit the listening device to be placed to and removed from the 5 ear.

8. In combination, a headgear attachment comprising two arms adapted to engage opposite sides of the head and pivoted with respect to each other, a listening device secured 10 at the end of one of said arms, a manually controlled member secured to said arm, an extension piece on the said arm, a second manually controlled member located with hand-grip distance of the first-named member, a link connecting the second-named member with said extension piece, a spring which normally tends to force the two manually controlled members apart to cause the 15 ends of said arms to approach towards each other, means whereby if said members are pressed together by the hand said arms are forced apart to permit the listening device to be placed to and removed from the ear, a spring controlled drum located at the end 20 of one of said arms distant from the pivot,

and a band of flexible material having one end secured to said drum and tensioned thereby and the other end secured to the end of the other arm distant from said pivot.

9. In combination, a listening device, a 30 headgear attachment for said listening device, a mouthpiece, and a flexible link for connecting said mouthpiece to said headgear attachment whereby when the listening device is placed to the ear the mouthpiece is placed 35 in front of the mouth.

10. In combination, a headgear attachment, a listening device secured to said headgear attachment, means tending to bring the 40 ends of said attachment towards each other, means located at one side of said headgear attachment to force the ends of said attachment apart and to permit the listening device to be placed on or removed from the head, a mouthpiece, and a flexible link connecting 45 said mouthpiece to said listening device.

In testimony whereof I hereunto affix my signature this 14th day of October, 1927.

DOUGLAS STUART SPENS STEUART.
